SAFETY RAZOR

Howard Addison Johnston, Toronto, Ontario,
Canada

Application August 22, 1932, Serial No. 629,870

8 Claims. (Cl. 30—12)

This invention relates to safety razors, and more particularly to that type in which a double edged flexible blade is clamped between a convex base plate and a concave cover plate. My object is to provide a razor in which the blade may be removed or replaced in an instant when so desired, but of such design that the blade cannot become loose accidentally by any amount of shaking such as occurs when the razor is rinsed after using and is shaken to remove the surplus water. Blades which are gripped by frictional devices holding one end of the blade sometimes loosen and fall out when vigorously shaken, due to the centrifugal forces developed by the movement, and the turning moment resulting from the gripping of the blade at a point distance from its centre of gravity.

I attain my object by providing a blade holder with a winged stud, and the blade with a central opening which will freely admit the stud and the wings when the blade is turned to a transverse position in relation to the holder. When the blade is placed over the stud and rotated about it, the wings engage the central portion of the blade, pressing it toward the holder and retaining it in that position. When the blade has been rotated about ninety degrees it reaches its shaving position and is locked there as follows: I provide openings in the blade at a distance from the center, and projections on the holder which enter the openings in the blade when it has reached the desired position. At the beginning of rotation of the blade about the stud the center of the blade is pressed toward the face of the holder by the spiral action of the wings, but the end portions of the blade are prevented from moving in the same direction because they are riding on the top of the aforesaid projections. These projections are diametrically opposite each other and are provided with a positive stop on the side to which the blade is being rotated and an easy slope on the opposite side.

As the blade is rotated farther about the stud, the openings in it are brought into register with the projections on the holder, whereby the trailing edge of each opening springs into engagement with the positive stop on the corresponding projection, thus preventing any further rotation. The leading edge of the opening, at the same time, engages the adjacent easy slope, and since no rotation of the blade in the opposite direction can take place without springing the blade upward against the slope, the trailing edge of the opening is held closely against the positive stop until it is intentionally removed.

The constructions are hereinafter more fully described and are illustrated in the accompanying drawing.

In the drawing like numbers of reference indicate corresponding parts in the different figures.

Fig. 1 is a side elevation of the razor in open position without the blade;

Fig. 2 a side elevation of the razor in closed position with the blade in shaving position;

Fig. 3 a section on line 3, 3 in Fig. 2;

Fig. 4 a section on line 4, 4 in Fig. 15;

Fig. 5 an enlarged side elevation of blade holder and blade;

Fig. 6 an enlarged section on line 6, 6 in Fig. 5;

Fig. 6a an enlarged section on line 6, 6 in Fig. 5, but with the blade in shaving position;

Fig. 7 an enlarged plan view of the blade holder;

Fig. 8 a longitudinal section of the holder in Fig. 7;

Fig. 9 an enlarged section on line 9, 9 in Fig. 8;

Fig. 10 a plan view of the preferred form of blade;

Figs. 11 and 12 plan views of modified forms of my blade;

Fig. 13 a plan view of another modification of my blade;

Fig. 14 an enlarged plan view of the preferred form of blade locked on the holder in shaving position; and

Fig. 15 a section on the longitudinal centerline of the razor in closed position, without the blade, part of the holder being shown in side elevation.

Referring to the drawing, the razor comprises a handle 1, which is attached to a base plate 2, on which is hinged a cover plate 3. The blade 4 is carried by a holder 5 which is hingedly mounted on the pintle of the first mentioned hinge to lie between the plates 2 and 3. The double hinge connection comprises a pintle 6 carried by spaced lugs 2^a on the base plate 2. The blade holder 5 is provided with two bent down bearing flanges 5^a which are disposed on the pintle between the lugs 2^a, and the cover plate is provided with a hinge knuckle 3^a also disposed on the pintle, between the bearing flanges 5^a. I provide a spring latch 8, pivoted at 9 on the free end of the cover plate 3, adapted to be sprung into engagement with the free end of the base plate 2, to lock the razor in shaving position.

I provide the blade holder 5 with a short stud 7, which projects from the upper surface thereof. The stud is provided with two blade retaining wings 7^a, which are partially of spiral form as shown in Fig. 9. The preferred method of construction is to affix a stamped metal winged cap 55

^{1b} to the top of the short stud ⁷, as shown in Fig. 8. The blade holder ⁵ is also provided with projections ^{5c} each of which has a substantially perpendicular face ^{5d} on one side and an easy slope ^{5e} on the other side. The blade holder is preferably formed by stamping it from sheet metal, thus providing the bearing and stiffening flanges ^{5f}, the projections ^{5c}, the short stud ⁷, and the slightly raised surface ^{5g} with one operation.

The base plate ² is made with a longitudinal channel ^{2b} into which the blade holder is received when the razor is closed. The blade holder is made to fit the inside of the channel and so prevent any lateral movement of the holder and blade when in the closed position as shown in Fig. 3.

The portion of the upper surface of the blade-holder ⁵ which is adjacent to the stud ⁷, is raised slightly above the surrounding general surface as shown at ^{5g}, Fig. 5, so that when the center of the blade ⁴ is pressed down by the lower part of the wings ^{7a}, the end portions of the blade will be engaged by the sloping face ^{5e} of the projections ^{5c} before coming into contact with the general surface of the holder as shown in Fig. 6a.

I provide the razor blade ⁴ with a symmetrical opening ^{4a}, transverse to the longitudinal axis of the blade, which opening may or may not be connected to other openings extending along the longitudinal center line. The preferred form consists of a small central opening ^{4a} and two diametrically opposite openings ^{4f} communicating with opposite ends of the central opening ^{4a} which extends transversely across the blade between the openings ^{4f}. The distance between the outer edges of the openings ^{4f} on a line transverse to the longitudinal center line of the blade is greater than the width of the transverse opening ^{4a}. The length of the said openings ^{4f} in a direction parallel to the said longitudinal center line is also greater than the width of the transverse opening ^{4a}. The preferred form of the opening formed by the openings ^{4b}, ^{4a}, ^{4f} may be described as resembling in shape the longitudinal section of a dumbbell, or the central portion and two opposite wings of a maltese cross. The opening is designed to permit the passage of the stud ⁷ and the wings ^{7a} when the blade is turned transverse to the holder. By reason of the fact that the parts of the opening distant from the center are larger than the central portion of the opening, lugs ^{4e} are formed on the blade projecting toward the center of the opening. These lugs are made to terminate at equal distances from the center of the blade, and give a bearing surface on the stud ⁷ when the blade is placed thereon.

Other openings ^{4b} are provided lying symmetrically on the longitudinal center line of the blade at a distance from the center. The opposite sides of these openings have inwardly directed fingers or shoulders ^{4d} and ^{4e} projecting towards one another and adapted to engage the faces ^{5d} and ^{5e} of the projections ^{5c} when the blade is in shaving position.

The cover plate ³ is provided with a projection ^{3b} on its concave side which is adapted to pass through the large end of the opening ^{4b} in the blade, and to engage the side walls of the channel in the base plate as shown in Fig. 4, to hold all three members in correct registration.

The razor is operated as follows:

Starting with the razor in open position as

shown in Fig. 1 the opening ^{4a} in the blade ⁴ is passed over the stud ⁷ and its wings ^{7a} while the blade is held in a position transverse to the holder. The blade is then rotated about the stud ⁷ in a counter-clockwise direction. The turned up edges of the wings ^{7a} first make contact with the lugs ^{4e} formed on the blade. As the blade is rotated further the central portion of it is sprung toward the body of the holder by the screw action of the wings ^{7a}, and the portions of the blade distant from the center ride on the projections ^{5c} carried by the holder, whereby the blade is dished longitudinally.

When the blade has been turned approximately ninety degrees, that is when its longitudinal center line becomes nearly parallel to the centre line of the holder, the openings ^{4b} in the blade ⁴ allow the end portions of the blade to spring toward the body of the holder ⁵. The shoulders or fingers ^{4e} on the leading edges of the openings ^{4b} follow down the easy slopes ^{5e} of the projections ^{5c} thereby bringing the other shoulders or fingers ^{4d} on the trailing edges of the opening into contact with the positive stops ^{5d} which prevents further motion in this direction of rotation. The pressure of the wings ^{7a} on the central portion of the blade tends to flex the blade longitudinally, whereby the shoulders or fingers ^{4e} are held in yielding engagement with the sloping faces ^{5e} and the shoulders or fingers ^{4d} are drawn toward and held in contact with the stops ^{5d}, as long as the blade remains in the holder. By forming the fingers ^{4d} and ^{4e} as previously described, greater flexibility of these fingers is obtained whereby any inaccuracies in the formation of the sloping faces ^{5e} will be compensated by the deflection of the flexible fingers without distorting the blade as a whole. The blade is now in shaving position on the holder as shown in Fig. 14.

The cover plate ³ is now moved to its closed position turning on pivot ⁸, and the spring catch ⁸ is sprung over the end of the base plate ² into the locked position as shown in Fig. 2. The razor is now ready for shaving. When it is desired to remove the blade the razor is opened, the blade is rotated 90 degrees in a clockwise direction and lifted from the holder.

It will be obvious that the exact form of the blade retaining means, and the exact form of the opening in the razor blade is unimportant in the application of this principle of blade retention. It is necessary only that the opening in the blade and the retaining surfaces be complementary to each other, and that while allowing free passage in one position, no passage is allowed when the blade is rotated. It is of material advantage for ease in placing the blade that the spiral, or screw form of blade retainer be used, but it is not essential. It should be understood therefore, that the invention is not limited to the exact details described, as many variations may be made by those skilled in the art without departing from the spirit of the invention.

What I claim as my invention is:

1. A safety razor having a carrier adapted to carry a blade having a non-circular opening therein; a blade retaining device adapted to pass through the said opening in the blade to engage the margin thereof upon a turning movement of the blade relative to the device; and a projection on the carrier having two faces opposite one another, one of the said faces being substantially normal to the surface of the carrier and the other face being inclined to the said surface in the direction of turning of the blade, the said

faces being adapted to be engaged by two shoulders spaced apart on the blade to tend to hold the blade from turning relative to the device, the engagement of the shoulder and inclined face 5 resulting in the other shoulder being held against the other face.

2. A safety razor having a blade carrier provided with a centrally located raised surface for supporting a blade in spaced relationship to the 10 surfaces underlying the blade at the end portions of the carrier, the blade having a non-circular opening therein; a blade retaining device adapted to pass through the said opening in the blade to engage the margin thereof upon a turning movement of the blade relative to the device; and projections on the end portions of the carrier, each projection having two faces opposite one another, one of the said faces being substantially normal to the aforesaid surface of an end 15 portion and the other face being inclined to the last mentioned surface in the direction of turning of the blade, the said faces on each projection being adapted to be engaged by two shoulders spaced apart on the blade, the shoulders in engagement with the inclined faces being located above the aforesaid surfaces of the end portions of the carrier so that they tend to hold the other shoulders in contact with the normal faces.

3. A safety razor having a carrier adapted to carry a blade having a non-circular opening therein; a blade retaining device adapted to pass through the said opening in the blade to engage the margin thereof upon a turning movement of the blade relative to the device; and projections 30 on the carrier at opposite sides of the retaining device, each projection having two faces opposite one another, one of the said faces being substantially normal to the surface of the carrier and the other face being inclined to the said surface 35 in the direction of turning of the blade, the said faces on each projection being adapted to be engaged by two shoulders spaced apart on the blade, the underside of the retaining device being helically inclined at one end thereof, the bottom of the inclination being below the tops of the projections so that the blade is moved to a position 40 below the tops of the projections and the engagement between the shoulders and the inclined faces tends to hold the other shoulders in 45 contact with the normal faces.

4. A safety razor provided with a blade carrier having a central fixed stud; and two diametrically opposed wings in fixed relationship to the stud and extending lengthwise of the carrier in 50 spaced relation to its adjacent surface, the under surface of each wing being inclined adjacent one side thereof to facilitate the engagement of the wing over a razor blade apertured in correspondence with the stud and wings and which 55 is adapted to be positioned thereover and then rotated.

5. A safety razor provided with a blade carrier having a central fixed stud; two diametrically opposed wings in fixed relationship to the stud and extending lengthwise of the carrier in spaced relation to its adjacent surface, the under surface of each wing being inclined adjacent one side thereof to facilitate the engagement of the wing over a razor blade apertured in correspondence with the stud and wings, and which 10 is adapted to be positioned thereover and then rotated; and a projection from the surface of the carrier adapted to spring into an opening in a razor blade to tend to resist a rotary movement of the blade relative to the holder.

6. The combination with a carrier as set forth 15 in claim 4, of a razor blade having a central opening formed therein shaped as a double key-hole slot with its axis at right angles to the length of the blade, the central portion of which is shaped to form a bearing for the stud of the 20 carrier while the enlarged portions of the slot are positioned diametrically opposite one another transversely of the blade, the said enlarged portions serving for the passage of the wings only when the blade is substantially at right angles 25 to the carrier.

7. The combination with a carrier as set forth 30 in claim 4, of a razor blade having a central opening formed therein shaped as a double key-hole slot with its axis at right angles to the length of the blade, the central portion of which is shaped to form a bearing for the stud of the 35 carrier while the enlarged portions of the slot are positioned diametrically opposite one another transversely of the blade, the said enlarged portions serving for the passage of the wings only when the blade is substantially at right angles to the carrier, the blade having a hole formed therein towards one end adapted to engage the 40 projection on the carrier.

8. A safety razor having a carrier adapted to carry a flexible blade; projections on the carrier having inclined faces on which edges of openings in the blade are adapted to rest; a blade retaining device located between the projections 45 on the carrier and adapted to pass through a non-circular opening in the blade to engage the margin of the said non-circular opening upon a relative turning movement of the blade and device, the underside of the device being helically inclined to flex the blade toward the carrier during said turning movement while the blade is being passed over the projections, the bottom of the said inclined underside being below 50 the tops of the projections so that the blade will spring into locking engagement with the projections when the said openings are brought into register therewith.

HOWARD ADDISON JOHNSTON. 60
